ELECTRIC SWITCH

Carl Appelberg, Stockholm, Sweden

Application July 21, 1939, Serial No. 285,795
In Sweden August 16, 1938

1 Claim. (Cl. 200—87)

The present invention relates to electromagnetically operated switches of the kind in which the break contacts together with the electromagnet armature are disposed within an evacuated or gas filled, substantially tubular container. The novelty of the invention consists therein, that the break contacts together with the motive members serving to actuate these contacts are mounted on a stand placed into the tubular container, which stand is intended to be introduced into the container from one end of the same so as to bear laterally on the walls of the container, while the electromagnet armature and the fixed terminal contacts inserted through the container are disposed on both sides of said stand at opposite ends of the container. Owing to this arrangement, the various parts of the switch can be easily mounted and adjusted before being placed into the container. Moreover, in this way the apparatus can be made extraordinarily compact so that the switch may in its entirety be enclosed in a tubular container having a comparatively small diameter, which fact is of great practical importance in many of those cases, in which electromagnetic switches of this kind are primarily intended to be used.

The invention will be more closely described with reference to the accompanying drawing, in which Figure 1 shows an embodiment of a switch according to the invention, Figure 2 shows a modification of the motive mechanism, Figure 3 shows a further modification of the motive mechanism.

Referring to Figure 1, the reference numeral 15 designates a hermetically sealed vessel or container which is either evacuated or contains a suitable inert gas. Within said container the different parts of the switch are arranged on a frame 16 of Steatite or other insulating material. The stationary contact 17 is connected by means of a fixed metal blade 18 with the inner end of a metal wire 19 melted into the glass wall, the end of said metal wire positioned externally of the container forming one terminal of the switch. The movable contact 20 is carried by a contact arm 21, which is pivotally mounted intermediate its ends on a pin 22 fixed in the frame 16. The lower end of the contact arm is connected to a second metal wire 23 melted into the glass wall, the external end of said wire forming the second terminal of the switch. A compression spring 24 strives to swing the contact arm 21 clockwise and to press the movable contact 20 against the fixed contact 17 under a suitable pressure. The contacts 17 and 20 are normally held apart by a

5 two-armed lever 25 which is journalled on a pin 26 fixed to the frame and which, through the intermediary of a roller 27 provided at the end of one of its arms, presses against an extension of the contact arm 21 under the action of a spring 28 one end of which is secured to the lever at the point 29 and the other end of which is secured to the frame at the point 30. The spring 28 is so dimensioned as to be capable of swinging 10 the contact arm 21 counter-clockwise while compressing the spring 24.

An electromagnet armature or iron core 35 in the form of an open-ended iron cylinder is guided for rectilinear movement in the container 15 and is adapted to be actuated by an electromagnet coil 36 provided externally of the container. A link 37 serves pivotally to connect the armature 35 with the two-armed lever 25 at the end thereof which is opposite to the one carrying 20 the roller 27.

The electro-magnet coil or solenoid 36 and the armature 35 are so dimensioned that upon energizing of the coil the armature will be pulled into the latter, the lever 25 being then rotated 25 counter-clockwise while tensioning the spring 28 until the lever comes to bear against a stop pin 38 secured in the frame. This will permit the movable contact arm 21 to rotate clockwise under the action of the spring 24 until the movable contact 20 engages with the stationary contact 17. The movement of the two-armed lever 25 under the action of the armature is interrupted through the engagement with the stop pin 38 only after 30 a certain play has been produced between the extension of the contact arm 21 and the roller 27, the fixing points 29 and 30 of the spring 28 being so positioned that the turning force exerted by the spring on the lever 25 is successively reduced according as the armature 35 is pulled into 35 the coil 36, so that said turning force will be a minimum when the lever 25 engages with the stop pin 38 upon complete attraction of the armature.

When the operating current passing through 45 the coil 36 is interrupted through the opening of a contact, not shown, provided in the operating circuit, the lever 25 is turned clockwise with an increasing force under the action of the spring 28, the armature being then pulled out of the coil while getting an increasing momentum, until 50 finally the roller 27 strikes against the extension of the contact arm 21, swinging the latter counter-clockwise against the action of the spring 24 whereby the movable contact 20 is removed from the fixed contact 17.

As will be clear from the drawing the movement transmitting system inserted between the armature 35 and the movable contact 20 is so dimensioned that the armature moves a considerably longer distance than the movable contact coupled therewith in that, on the one hand, the angle lever 25 is provided with arms of considerably different length and, on the other hand, said angle lever actuates the swingable contact arm 21 at a point which is positioned farther away from the pivot 22 than is the movable contact 20.

The extension of the contact arm 21 forms together with the angle lever 25 a cam device the two mutually cooperating parts of which are out of engagement with each other when the armature takes up its attracted position, involving that the cam device operates with a certain play.

According to Figure 1, the desired reduction of movement of the movable contact has been obtained mainly through a suitable dimensioning of the lengths of the various levers of the coupling. It should be clear, however, that a considerable part or even the greater part of the desired movement reduction can be included in the cam device proper. For example, the angle lever 25 can be designed so that the line between the swinging axis 26 and the point where the roller 27 engages with the extension of the contact arm 21 forms a greater angle with the said extension, thereby reducing, for a certain turning of the angle lever, the component of movement of the roller which is perpendicular to the extension.

An embodiment in which the main part of the movement reduction is included in the cam device is shown in Figure 2. According to this arrangement the movable cam member consists of a one-armed lever 40 which is pivotally mounted at one of its ends on a shaft 41 secured in the frame. At its free end the lever carries a roller 42. At a point between the shaft 41 and the roller 42 the lever 40 is connected by means of a link 43 with the electromagnet armature 35. A spring 44 normally holds the lever 40 in engage-

ment with a stop pin 45 secured in the frame. Upon energization of the coil 36 the armature 35 will be pulled into the coil, the lever 40 being then swung clockwise while tensioning the spring 44, causing the roller 42 to strike against a bent extension of the movable contact arm 21, which serves as the fixed cam member, and to roll along said extension while swinging the contact arm counter-clockwise against the action of the spring which actuates the same. By suitably shaping the bent extension each desired ratio between the movement of the armature 35 and the movement of the movable contact 20 may be obtained.

The switch according to Figure 3 differs from the one just described substantially only therein that the extension of the contact arm 21 serving as a fixed cam member carries a roller 46, whereas the curved cam surface is provided on the movable cam member 47, the latter being made in the form of a single-armed lever.

It is believed in view of the foregoing description that a further detailed description of the operation of the invention is unnecessary. Likewise it is believed that the advantages of the invention will be readily apparent.

Having thus fully described the invention what is claimed as new and desired to be secured by Letters Patent is:

An electric switch comprising in combination, 30 a hermetically closed tubular container, a magnet coil arranged outside the container, a spring actuated armature longitudinally slidable inside the container at one end thereof, electrical terminals extending into the container at the opposite end thereof, a switch frame mounted in an intermediate portion of the container, switch contacts mounted on said frame including a contact arm swingable transversely of the container and extending longitudinally into a space provided between the switch frame and the armature, and a contact operating mechanism mounted in said space on the end of said frame and adapted to be actuated by the armature to shift said contact arm.

CARL APPELBERG.
